Inventor,
G. R. Watson, by
G. Kennedy,
Attorney.

UNITED STATES PATENT OFFICE.

GEORGE R. WATSON, OF WATERLOO, IOWA, ASSIGNOR TO ARMSTRONG MANUFACTURING COMPANY, OF WATERLOO, IOWA.

DRILL BIT.

Application filed June 19, 1924. Serial No. 720,975.

To all whom it may concern:

Be it known that I, GEORGE R. WATSON, a citizen of the United States of America, and a resident of Waterloo, Black Hawk County, 5 Iowa, have invented certain new and useful Improvements in Drill Bits, of which the following is a specification.

My invention relates to improvements in drill-bits, and the object of my improvement 10 is to supply a bit for a drill such as is used in drilling wells through rock strata, which shall have such a combination of crushing means and cutting means as will cooperate most efficiently and rapidly in the work of 15 drilling.

This object I have accomplished by the means which are hereinafter described and claimed, and which are illustrated in the accompanying drawings, in which Fig. 1 is a 20 side elevation of a drill having my improved bit, with part of the drill body broken away, and Fig. 2 is an elevation of the same taken at an angle of ninety degrees to the elevation shown in said Fig. 1. Fig. 3 is a plan of the 25 bit face.

The shank 1 of the drill has a coned and exteriorly threaded boss 2 for intermeshing with a threaded socket in a drill-stem. The body 3 of the drill is of octangular shape in 30 cross section with two opposite faces provided with longitudinal grooves 4 starting from said shank 1 and extending downwardly to open through the flat crushing end-face 5 of the bit, the bit-end 5 being of 35 larger diameter than the shank and body of the drill, with cylindrical outer wall having the opposite clefts 9 which are considerably narrower than the grooves 4.

The lower ends of the grooves 4 terminate 40 above the crushing face 5 and the cylindrical wall thereabove in a concave or arcuate anticlinal diametrical ridge 7-8, whereby the crushing face of the bit is divided into like somewhat crescental halves 5 in the same 45 transverse plane with the middle interspace wider than said side clefts or openings 9. Alined diametrically with the arcuate ridge 7-8 but below it at either side and extending 50 across the crushing faces 5 are like straight anticlinal cutter ridges 10 having a rather wide angle. The inner ends of these ridges 10 may be inclined as at 11.

As the cutter ridges 10 project downwardly from the flat crushing faces they chop up the rock at the bottom of the drill-hole as the 55 drill rises and is dropped, and then the crushing faces 5 crush and reduce to powder the detached fragments of rock most efficiently as none can escape in any way or direction, because the widened end of the 60 bit nearly fits the bore of the drill-hole. As the part 5 has a cylindrical outer wall which is interrupted on opposite sides only by the relatively narrow clefts 9, the edges of the latter may ream out the hole cylindrically, 65 the clefts not being wide enough to stall or shape flat places in the wall of the hole. The side grooves 4 are of ample size to hold and convey sufficient water to the bottom of the bore about the bit, while the arcuate cutter 70 7-8 breaks up the rocky cone all the time forming in the bottom of the drill-hole.

Having described my invention, what I claim as new, and desire to secure by Letters Patent, is:

1. A drill-bit having a flat crushing-face, and having side grooves terminating above said crushing-face in an arcuate anticlinal ridge, and said crushing-face having anticlinal ridges extending across it.

2. A drill-bit having a flat crushing-face and a pair of ridges thereon in diametrical alinement with their inner ends spaced apart, the crushing-face having an opening extending diametrically across it and separating said ridges medially and transversely to provide therebetween a concave anticlinal cutter.

3. A drill-bit whose body is terminally widened to provide a like pair of substantially crescental reamers with a flat crushing face, whose interspace is bridged by a diametrically positioned upwardly arcuate anticlinal ridge, said body having on opposite sides longitudinal grooves terminating below 95 at said arcuate ridge, with the end interspaces of the crescental parts narrower than said grooves to prevent the drill from forming flat spots in the wall of a drill-hole.

Signed at Waterloo, Iowa, this 15th day 100 of May, 1924.

GEORGE R. WATSON.
